UNITED STATES PATENT OFFICE

2,326,212

CHLORINATOR

Joseph Garelick, Hurleyville, N. Y.

Application June 11, 1941, Serial No. 397,528

3 Claims. (Cl. 210—28)

This invention relates to the treatment of water with chlorine in liquid form for the purpose of sterilizing the water.

An object of this invention is to provide means for handling chlorine solutions with safety and in such manner that the admission of the chlorine solution is visible and may be controlled to a very fine degree.

Another object of this invention is to provide an apparatus for introducing chlorine solutions into a stream of water in predetermined ratio to the quantity of water flowing in a suction line, and so that for any given quantity of water flowing in the suction line a given weight of chlorine solution will be introduced.

Another object of this invention is to provide a liquid feeding device of the character referred to, which is of extremely simple construction, inexpensive to manufacture, has no moving parts and is automatic in its action.

Another object of this invention is to provide a chlorinator made of glass and clay containers and hard rubber tubing and which will be resistant to the corrosive action of the chlorine and provide safe operation.

With the above and other objects in view, the invention will be hereinafter more particularly described, and the combination and arrangement of parts will be shown in the accompanying drawing and pointed out in the claims which form part of this specification.

The drawing is a front elevation of the chlorinator, the reservoir and the flow visibility container being in cross-section.

In the illustrated embodiment of the invention, the numeral 10 indicates a bottle containing a reserve supply of chlorine solution which it is desired to add in small quantities to the fluid passing through a suction line 11 connected to a pump P.

Mounted below the bottle 10 is a reservoir or receiving vessel 12 having a liquid level 13 which is to be maintained constant. For this purpose the bottle 10 is supported in the inverted position shown in the drawing, with the neck 14 of the bottle extending into the reservoir and with the mouth 15 sealed by the liquid therein.

As the liquid is drawn from the reservoir 12 its level is lowered. When the liquid level falls below the mouth 15, air passes into the bottle and liquid is permitted to flow therefrom until the level of the liquid in the reservoir reaches the bottle mouth 15 and seals it.

Chlorine solution is periodically drawn from the bottle 10, the flow of chlorine solution from

the reservoir 12 controlling the flow of chlorine solution from the bottle. The level 13 of the chlorine solution in the reservoir 12 is thus maintained constant by the inverted bottle action.

5 A two-member siphon tube comprising a shorter leg 16 and a longer leg 16' is supported above the bottle 10 and the reservoir 12 by means of a transparent container 17 having a perforated cover 18 in which end portions of the said siphon tube members are suitably received in air-tight engagement.

The container 17 is preferably made of glass whereby it is resistant to corrosion. The container 17 is mounted in an upright position on a bracket 19 at the upper end portion of a frame 20 which also supports the bottle 10 and the reservoir 12 and forms a self-contained chlorinating unit.

10 The receiving end of the lower end 21 of the shorter leg 16 is submerged in the reservoir 12. The upper end 22 of the shorter leg 16 terminates in considerably spaced relation from the bottom of the container 17. The upper end 23 of the longer leg 16' terminates in slightly spaced relation from the bottom of the container 17. The lower end 24 of the longer leg 16' is connected to the suction line 11.

15 In operation, service water to be chlorinated, passing through the main 11 causes a suction in the leg 16' and a partial vacuum is formed in the container 17 whereby the liquid in the reservoir 12 is caused to be sucked up and delivered from the reservoir in the form of visible drops 25. The drops accumulate at the bottom of the container 17 and form a layer of chlorine liquid 26 on the bottom of said container sufficient to immerse the end of the leg 16' in said container when a continuous feeding action takes place.

20 The visibly issuing drops 25 of the sterilizing liquid are at all times clearly seen through the glass container 17 and thereby assure the user that the sterilizing apparatus is performing its duty, while correspondingly warning of accidental failure of proper operation.

25 A petcock or valve 27 in the shorter leg 16 serves for controlling the flow of the sterilizing liquid to a very fine degree. The chlorine solution is thus introduced in predetermined ratio in accordance with the water supply flowing in the suction line.

30 The bottle 10 is carried and held bodily in a crate 28 while the neck of the bottle is entirely without the crate. The crate may be sup-

ported in any suitable manner to the frame 29 such as by brackets 29 and bolts 30.

The reservoir 12 is preferably a clay pot. The two members of the siphon tube may comprise Bakelite tubing and rubber hose having a degree of rigidity which will prevent collapse of same in service.

It will thus be seen that there has been provided a chlorinator which maintains the feed of chlorine for which it is set absolutely constant and uniform until it is reset to feed another amount.

In accordance with the patent statutes I have described and illustrated the preferred embodiment of my invention, but it will be understood that various changes and modifications can be made therein without departing from the spirit of the invention as defined by the appended claims.

I claim:

1. An apparatus of the class described for feeding a chlorine solution into a stream of water, comprising a reservoir and an inverted bottle of reserve supply chlorine solution, means for supporting said bottle by engagement with the body portion thereof, said supporting means being in spaced relation from the neck of said bottle to avoid contact of said neck with said holding means, said bottle being positioned with the neck thereof extending into said reservoir and with the entire lower surface of the mouth portion of said bottle positioned below the upper surface of said chlorine solution, said lower surface being wholly immersed in and in full contact with the chlorine solution in said reservoir, said mouth being sealed by said chlorine solution for maintaining chlorine solution at a constant level in said reservoir, a siphon tube having the lower end of its shorter leg immersed in the chlorine solution in said reservoir, a suction line for the flow of water to be treated, the longer leg of said siphon tube being connected with said suction line, suction means in said suction line for causing actuation of said siphon, means in said shorter leg for regulating the flow of said solution, said siphon tube comprising two members, and an upright transparent container having means for receiving end portions of said siphon tube members in air tight engagement, the upper end of said longer leg terminating in slightly spaced relation from the bottom of said transparent container, the upper end of said shorter leg terminating in considerably spaced relation from the bottom of said transparent container to permit visible observation of the rate of feed of said chlorine solution passing through said transparent container, said siphoning legs and said transparent container connect-

ing said legs and the connection to said suction line being air tight and closed to air.

2. In an apparatus of the class described for feeding a chlorine solution into a stream of water, comprising a supporting means, a reservoir and an inverted bottle of reserve supply chlorine solution held bodily by said supporting means above said reservoir, said bottle being positioned with the neck thereof extending into said reservoir and with the mouth sealed by said solution for maintaining chlorine solution at a constant level in said reservoir, a siphon tube having siphoning legs of unequal length, the lower end of its shorter leg immersed in the chlorine solution in said reservoir, a suction line for the flow of water to be treated, the longer leg of said siphon tube being connected with said suction line, suction means in said suction line for causing actuation of said siphon, means in said shorter leg for regulating the flow of said solution, said siphon tube comprising two members, an upright transparent container having means for receiving end portions of said siphon tube members in airtight engagement, the upper end of said longer leg terminating in slightly spaced relation from the bottom of said transparent container, the upper end of said shorter leg terminating in considerably spaced relation from the bottom of said transparent container to permit visible observation of the rate of feed of said chlorine solution passing through said transparent container, said siphoning legs and said transparent container connecting said legs and the connection to said suction line being air tight and closed to the air.

3. In an apparatus for feeding chlorine solution into a water suction pipe, comprising a reservoir for chlorine solution, means for maintaining said chlorine solution at a constant level in said reservoir, a two-member siphon tube having its shorter leg member immersed in said chlorine solution, a container having means for receiving end portions of said siphon tube members, a suction pipe for the flow of water to be treated, the longer leg member of said two-member siphon tube being connected in air-tight engagement with said suction pipe, means for regulating the flow of said solution, said siphon tube members being connected to said container in air-tight engagement, end portions of said siphon tube members in said container terminating at different levels to permit a quantity of said chlorine solution to remain in said container during said siphon action, the inlet to said longer leg being immersed in chlorine solution in said container, and suction means in said water suction pipe for causing actuation of said siphon.

JOSEPH GARELICK.
